UNITED STATES PATENT OFFICE.

WILHELM MAYBACH, OF CANNSTADT, GERMANY.

MOTOR-VEHICLE.

SPECIFICATION forming part of Letters Patent No. 703,436, dated July 1, 1902.

Application filed March 31, 1902. Serial No. 100,746. (No model.)

To all whom it may concern:

Be it known that I, WILHELM MAYBACH, a subject of the King of Würtemberg, and a resident of Cannstadt, in the Kingdom of Würtemberg, German Empire, have invented certain new and useful Improvements in Motor-Vehicles, of which the following is an exact specification.

My invention relates to improvements in motor-vehicles, and more especially to an arrangement for sucking air through the cooling apparatus for the motor; and it consists in the arrangement of an air-tight protecting-box around the motor, in the front wall of which box the water-cooler is situated, while in the back wall of the same a ventilator is arranged, by means of which air is sucked into the protecting-box of the motor and pumped out of the box, together with the exhalations of the motor.

My invention is represented in the accompanying drawing, which shows a vertical longitudinal section through the motor and the protecting-box surrounding the same. It is known already to surround the motor of motor-vehicles with a protecting-box, and it is also known to arrange a ventilator behind the cooling apparatus, which ventilator has the purpose of sucking a great quantity of air with great velocity through the cooling elements in case the velocity of the air produced by the speed of the vehicle is not sufficient for cooling the cooling-water. In all constructions, however, the air heated by passing through the cooling apparatus, as well as the exhalations of the motor and the emanations of the lubricating-oil, leave the protecting-box through openings provided in the side walls and in the doors of the protecting-box and in consequence thereof incommodate the people sitting in the carriage. According to my invention this disadvantage is overcome by pumping the hot air, together with the exhalations of the motor, out of the protecting-box surrounding the same, so that this air leaves the box on the back wall of the same underneath the chest of the carriage.

The arrangement has, furthermore, the advantage that the formation of a vacuum behind the motor—*i. e.*, behind the lower part of the same—and the whirling movement of the air caused by this vacuum, which move-

ment causes a whirling up of the dust, is perfectly avoided.

In the drawing, *a* is the motor, surrounded by the protecting-box *b*. In the front wall of this box the well-known water-cooler *c* is arranged, while in the back wall a ventilator *d* is situated. This ventilator sucks fresh air from the front side of the carriage through the water-cooler *c* and brings the same, together with the exhalations of the motor, under the carriage-chest, where the exhalations can no more incommodate the people sitting in the carriage.

In the construction shown in the drawing the ventilator is formed by arranging vanes *e* on the circumference of the fly-wheel of the motor. In case the position of these vanes is adjusted so that in case the motor runs with its normal speed the velocity of the air leaving the protecting-box is equal to the speed of the carriage the ventilator has only to do the work necessary for sucking the air through the cooling apparatus, as this ventilator does not find any resistance in pumping the air out of the protecting-box.

Having thus fully described the nature of my invention, what I desire to secure by Letters Patent of the United States is—

1. In motor-vehicles, the arrangement of a motor surrounded by a protecting-box, a water-cooler situated in the front wall of this box, and a ventilator situated underneath the chest of the carriage in the back wall of the protecting-box, substantially as described and for the purpose set forth.

2. In motor-vehicles, the arrangement of a motor surrounded by a protecting-box, a water-cooler situated in the front wall of this box, a fly-wheel for the motor situated underneath the chest of the carriage in the back wall of the protecting-box, said fly-wheel being provided with ventilator-vanes on its circumference, substantially as described and for the purpose set forth.

In testimony whereof I have signed my name to this specification in the presence of two subscribing witnesses.

WILHELM MAYBACH.
